COMBINED WORK HOLDER AND CLAMP

Joseph Folk, La Porte, Ind., assignor to U. S.
Slicing Machine Company, La Porte, Ind., a
corporation of Indiana

Application July 3, 1930, Serial No. 465,597

19 Claims. (Cl. 146—217)

The present invention relates to slicing machines and particularly to that class of slicing machine in which the substance is mounted on a reciprocating carriage and carried past the slicing knife when the carriage is moved. However, the invention is equally applicable to a slicing machine in which the work holder is stationary and the knife moves relatively thereto. This application is a continuation in part 10 of my co-pending application Serial No. 464, 823 filed June 30, 1930.

In that co-pending application I have shown a novel form of work holder which I am disclosing and claiming in this application. In 15 addition I have shown in this application a modification of that work holder. One object of this invention is to provide a novel form of work holder for clamping a substance on the bottom thereof.

Another object of this invention is to provide a work holder which may clamp any one of a plurality of sides of a substance with equal effectiveness.

Another object of this invention resides in the 25 provision of a single operating means for moving the substance holder past the knife and simultaneously moving the substance towards the cutting plane of the knife.

Another object of this invention is to provide 30 a substance clamp which acts also as a substance support.

More specifically an object of this invention is to provide a work clamp embodied in a work holder in such a manner that the same acts 35 as a part of the supporting surface of the work holder as well as a clamping means for the substance to be sliced, preferably this substance clamp is adapted to occupy a plurality of positions in each of which the substance may be clamped firmly thereby.

A still further object of this invention is to provide a work clamp for the substance being sliced and provide means for moving said clamp to position the substance in various angular positions on the work holder in each of which the substance is in operative position to be sliced by the slicing knife.

Other objects of this invention will appear hereinafter as the description thereof proceeds.

50 In the drawings—

Fig. 1 is an elevational view of a slicing machine embodying my invention;

Fig. 2 is an end elevation of the device shown in Fig. 1 and looking from the left in that figure;

Fig. 3 is a view looking in the direction 3—3 of Fig. 1;

Fig. 4 is a section taken along the line 4—4 of Fig. 3;

Fig. 5 is an enlarged view taken substantially 5 along the line 5—5 of Fig. 3;

Fig. 6 is a fragmentary elevational view showing a modified form of my invention;

Fig. 7 is a view looking substantially in the direction 7—7 of Fig. 6 showing the work holder 10 in cross-section substantially along the line AB in Fig. 8;

Fig. 8 is a section taken substantially along the line 8—8 of Fig. 7; and

Fig. 9 is a section taken substantially along the line 9—9 of Fig. 8.

Referring now more particularly to Figs. 1 to 4 inclusive, it will be noted that the slicing machine comprises a base member 1 supported by the rubber pads or feet 2. A bracket 3 has the 20 upstanding members 4 secured to the base in any suitable manner and is adapted to carry a guide rod 5, the upper surface of which is shielded by the cover portion 6 of the bracket 3.

A guide bar 7 is secured by means of the 25 screws 8 to the base 1 and is substantially square in cross-section as best illustrated in Fig. 2. A bracket 9 has a bearing portion 10 surrounding the guide rod 5 and has another portion engaging the upper surface of the guide bar 7. The 30 bracket 9 also has a plate 11 secured thereto by means of a screw 12 to form with the portion of the bracket 9 which engages the upper surface of the guide bar 7, a second guiding means for the bracket 9 and a means whereby the turning movement of the bracket 9 about the guide rod 5 is prevented. This arrangement permits the bracket 9 to be reciprocated along the guide rod 5 and the guide bar 7 in a rectilinear path.

The bracket 9 is adapted to support the work 40 holder. This work holder comprises a casting 13 having the integral bosses 14 and bolts 15 extending through the bracket 9 and into the bosses 14 for securing the casting 13 to the bracket 9.

A gage plate 16 mounted on a shaft 17 is moved longitudinally in the direction of the shaft 17 by means of an operating knob 18. The shaft 17 is mounted in a bracket 19 secured to the base 1. The gage plate is provided with a 50 plurality of grooves 20 on one face thereof. A rotating knife 21 is driven by a motor 22 in the manner shown in my aforementioned co-pending application or in any other suitable manner. A guard 23 protects the rear edge of the 55

knife and is movable to an inoperative position to permit the grinders 24 of the grinding unit 26 to operate on the upper edge of the knife.

A second guard 27 is mounted on the edge 5 of the gage plate 16 which lies adjacent the knife and is secured thereto in any suitable manner. A rubbing plate 28 is detachably secured to the bracket 3 and is provided with grooves 29 on one face thereof. The mechanism so far 10 described in a general way is more specifically described in my aforesaid copending application, and it is believed that no further description of these parts is necessary in this application as the claims in this application are limited 15 to the work holder and clamp used for holding the substance while it is being sliced.

I will now proceed to describe the novel form 20 of work holder used for holding the substance in a position to be sliced. The casting 13 of the work holder has the upper surface thereof substantially V-shaped in cross-section as best 25 illustrated in Fig. 1, and is covered by means of a plate 30 secured thereto by means of suitable bolts 31. As best illustrated in Fig. 3, there is a large rectangular opening 31' in the plate 30 and also in the casting 13 for the reception 30 of the work clamp, designated generally as 32.

The casting 13 also supports the guide rods 33 and 34 which extend in a direction substantially perpendicular to the direction of the guide rod 5 or in a direction substantially perpendicular to the cutting plane of the knife. A frame 35 has a bearing portion 36 surrounding the guide rod 33 and a bearing portion 37 surrounding the guide rod 34 on three sides thereof. The guide bars 33 and 34 are adapted to 35 guide the frame 35 in a rectilinear path to and from the cutting plane of the knife.

The frame 35 carries the upstanding lugs 38, 40 and these support a pivot rod 39. This pivot rod 39 has the arms 40 pivoted thereto. These arms 40 are secured to the depending flange 41 which surrounds the plate 42 of the work 45 clamp 32. The depending flange 41 extends all of the way round the plate 42 and rotatably carries the shafts 43. Gears 44 secured to the shafts 43 at one end thereof mesh with each other so that when one of the shafts is rotated the others will be rotated also, adjacent shafts 50 being rotated in opposite directions.

Each of the shafts carry a plurality of prongs 45. A handle 46 on a rod 47 screw threaded into one of the shafts 43 and locked in place by a nut 48 is adapted to be used for the purpose of rotating the shaft to which it is secured, and as a consequence, all of the other shafts by means of the gears 44. When the shafts 43 are rotated by moving the handle 46 in Fig. 4 in a counter-clockwise direction, the prongs 45 will move through the openings 49 in the plate 42 so that if a substance is placed on the plate 42, the prongs will engage the substance and as the movement of the shafts continues, the prongs will draw the substance against the surface of the plate in the manner best described in the patent to Luschka et al., No. 1,356,165 patented October 19, 1920.

The frame 35 is provided with a handle 50 secured thereto by the screws 51 and by means 70 of this handle the frame may be moved along the guide bars 33 and 34 towards the cutting plane of the knife, and at the same time the work holder may be moved in the direction of the guide rod 5 to carry the work holder past the slicing knife so as to cut a slice from the sub-

stance mounted on the work holder. In other words, the substance may be placed upon the clamp 32 and secured to the plate 42 by moving the handle 46 in a counterclockwise direction as viewed in Fig. 4. Thereafter the substance may be moved simultaneously in two directions by the operator merely actuating the handle 50. This leaves the operator's other hand free to catch the slice as it is formed and carry the same towards the rear of the machine so as to prevent buckling of the slice, and to enable the operator to cut more uniform slices from the substance being sliced. This feature is very clearly brought forth in my aforesaid copending application.

It will be noted however, that when the frame 35 has moved to its extreme left hand position, there is still a considerable portion of the substance which has to be sliced. In order to do this I provide means whereby the work clamp may be moved so that the plate 42 is in a vertical position or in a position parallel to the cutting plane of the knife. After being moved to this position, the work clamp operates substantially in the same manner as in the aforementioned patent to Luschka, et al.

The means which I employ to produce the last mentioned result is as follows: The clamp 32 as previously set forth is pivoted by means of the arms 40 to the pivot rod 39. This enables the clamp 42 to be quickly moved from a position in the plane of the plate 30 to a position at substantially right angles thereto. Along one side of the clamp I arrange the extension links 52 and 53 pivoted to each other at 54 and to the frame 35 and depending flange 41 respectively at 55 and 56. A stop 57 on the link 52 is adapted to engage within the notch 58 in the link 53 to limit the movement of the links relatively to each other when the work clamp 32 is moved to the dotted line position shown in Fig. 4. Preferably the links when in their extended position shown in dotted lines in Fig. 4 have the center of their common pivot 54 located slightly to the left of a line drawn through the centers of the pivots 55 and 56 so as to prevent accidental movement of the clamp 42 from the dotted line position to the full line position shown in Fig. 4 while a substance is being sliced.

It will be noted that when the substance clamp 50 is in the position shown in Fig. 4, the substance may be moved towards the cutting plane of the knife, the same as before, the forward edge of the slice being supported by means of the supporting edge 59 of the plate 30. With this arrangement practically all of the substance may be sliced as is more clearly set forth in the patent to Luschka referred to above. Obviously the work holder does not have to be V-shaped in cross-section because the clamp will work 60 equally as well with a work holder having a horizontal supporting surface, or a supporting surface which extends downwardly towards the cutting plane of the knife. Nor does the cutting plane of the knife have to be vertical as illustrated in the drawings.

The frame 35 is provided with an adjustable stop 60 screw threaded in a boss 61 and locked in place by means of a lock nut 62. This stop 60 is adapted to engage one of the shafts 43 when the clamp 32 is in the position shown in Fig. 4. By regulating the height of the stop 60, the position of the plate 42 with respect to the plane of the plate 30 may be regulated within certain limits to thereby position the plate 42 75

in the best position for clamping the substance. It may be found that the clamp will operate better with the plate 42 either slightly above or slightly below the supporting surface of the plate 30, and the stop 60 is the means for regulating the amount of this adjustment.

With some substances satisfactory slices may be obtained by slicing the substance without regard to the direction in which the fibers of the substance extend and in other substances which do not have any fibers the direction in which the slice is taken is practically immaterial. Therefore, I desire to provide a clamp which may be used to clamp such substances as it is moved towards the cutting plane of the knife and while the clamp is in the plane of the supporting surface of the work holder and may be so moved as to enable one to position the clamp in a position parallel to the cutting plane of the knife without the necessity of re-clamping the substance after the substance has been moved forwardly as far as possible while the clamp is in the plane of the supporting surface of the work holder. In Figs. 6 to 9 inclusive, I have shown such a work holder and this work holder necessitates only the modification of the connection between the work holder and the frame which slides on the guide bars 33 and 34. In this modification the same reference numerals refer to the corresponding parts in Figs. 1 to 5 inclusive.

The work clamp is substantially the same as shown in Figs. 1 to 5 inclusive, but is attached to the pivot rod in a different manner. To the depending flange 41, I secure an angle bracket 63 by means of screws 64. On the pivot rod 39 are pivoted the arms 65 which carry the integral plate 66 having the elongated slots 67 arranged therein in the manner best illustrated in Fig. 7. Thumb screws 68 extend through slots 67 and are threaded into the angle brackets 63 as best illustrated in Fig. 8. Flanges 69 integral with the thumb screws 68 are adapted to abut against the plate 66 adjacent the edges of the slots 67 so that when the thumb screws 68 are tightened, the plate 66 is held firmly in engagement with the angle bracket 63 and consequently the clamp 32 must move with the plate 66 as it moves about the pivot 39 or with the frame 35. By loosening the thumb screws 68 the clamp 32 may be moved closer to or farther away from the pivot rod 39 as may be desired, the slots 67 limiting the amount of permitted movement.

When using this modified form of clamp the parts are normally arranged in the position shown in Fig. 8 and during the slicing operation the plate 32 is in a position substantially flush with the supporting plate 30, the substance being moved towards the cutting plane of the knife the same as with the embodiment shown in Figs. 1 to 5 inclusive. However, when the frame 35 has reached its extreme left hand position in Fig. 8 one may merely release the thumb screws 68 and move the clamp 32 to the right while at the same time holding the frame 35 stationary. The position of the clamp 32 will then be as shown in dotted lines at C in Fig. 8 and the substance clamped thereon will occupy the position shown in dotted lines at E in Fig. 8. After tightening the thumb screws 68 the work holder can be swung upwardly about the pivot rod 39 to position the clamp in a vertical plane such as at D shown in Fig. 8 only at a more remote position

than shown in Fig. 8 in order that the substance will be clear of the knife.

With the modification of the invention shown in Figs. 7, 8, and 9, it is obvious as with the first form of the invention that the clamp cannot be moved a sufficient distance toward the cutting plane of the knife to slice all of the substance which extends between the flange 41 and the cutting plane of the knife. Therefore if an attempt were made to move the clamp to the dotted line position shown in Fig. 8 without reclamping the substance, the portion of the substance lying between the cutting plane of the knife and the flange 41 would prevent the pivoting of the clamp about the pivot 39. Therefore, by sliding the clamp with respect to its support to the dotted horizontal position, shown in Fig. 8, with the substance clamped thereon, the clamp 10 can then be pivoted to the vertical dotted line position shown in that figure without reclamping the substance. Of course, it will be understood that in addition to moving the clamp into the vertical position shown by dotted lines in Fig. 8, the frame which carries the clamp is moved toward the rear of the machine in order that the substance will be moved far enough away from the slicing knife so as not to abut thereagainst.

In order to hold the clamp in desired position other than a position within the plate 30, I provide a plurality of links 70 and 71 pivoted to each other at 72 and to the frame and clamp respectively at 73 and 74. The pivot 72 is a thumb screw having an operating head 75. The stem portion of the thumb screw is screw threaded into a boss 76 on the link 71 and passes freely through the link 70. Since the links 70 and 71 may be held rigidly in any angular adjustment relatively to each other, it is obvious that the clamp 32 may be held in any position of adjustment within the permitted movement thereof. Thus if desired slices may be cut from a substance while the same is held at an angle to the cutting plane as well as at an angle to the work holder.

It is obvious that the device shown in Figs. 6 to 9 inclusive may be used in the same manner as the device shown in Figs. 1 to 5 inclusive, by merely clamping the parts together in the position shown in Fig. 8 and permitting them to remain in that position. If desired the links 52 and 53 shown with the modification illustrated in Figs. 1 to 5 inclusive, may be provided with a thumb screw in place of the pivot 54.

Obviously those skilled in the art to which this invention pertains may make other changes in the invention without departing from the spirit thereof or the scope of the appended claims.

Having thus fully described my invention, what I desire to secure by Letters Patent of the United States is:

1. In a work support for slicing machines, the combination with a plate having an opening therein, of a frame slidably mounted in said opening for movement substantially parallel to the supporting surface of said plate, and a supporting member mounted on said frame and adapted to occupy a position in substantially the same plane as said plate, said member being also movably mounted on said frame for movement to a position at an angle to said plate, and means for clamping a substance against said member while said member is in either of said positions.

2. In a work support for slicing machines, the combination with a plate having an opening

- therein, of a frame slidably mounted in said opening for movement substantially parallel to the supporting surface of said plate, and a supporting member mounted on said frame and 5 adapted to occupy a position in substantially the same plane as said plate, said member being also movably mounted on said frame for movement to a position at an angle to said plate, and means for clamping a substance against 10 said member while said member is in either of said positions, said mounting for said member being such that the substance may remain clamped thereon while the member is being moved from one position to the other.
- 15 3. A substance clamp for slicing machines comprising a trough having two flat angularly disposed supporting members, one of said members having an opening therein, guides arranged in said opening, a frame slidable on said guides, a plate pivoted to said frame so as to be movable from a position substantially parallel with 20 said last mentioned member and to a position at an angle thereto, and clamping means co-operating with said plate for holding a substance thereon.
- 25 4. A work holder for slicing machines comprising a plate having an opening therein, a frame guided for movement in said opening, a clamp extensibly and pivotally mounted on said frame, and means for holding said clamp in various angular positions about its pivot so as to 30 present a different portion of a substance being sliced in a position to be sliced without re-clamping the substance.
- 35 5. A work holder for slicing machines comprising a supporting plate having an elongated opening therein, a frame guided for movement in said elongated opening, a bracket pivoted to said frame, a clamp adjustably mounted on said bracket for movement towards and away from 40 said pivot, means for holding said clamp in adjusted position relative to said bracket, means for holding a substance against a surface of said clamp, and means for actuating said frame.
- 45 6. A work holder for slicing machines, comprising a work support and a movable clamp, means for moving the clamp, said clamp having means thereon for engaging and holding the substance solely by its own action, means constraining the clamp to move with said support at all times, said clamp having permitted angular movement with respect to said work support, means for holding said clamp in various angular positions relative to the supporting surface 50 of said work support including a position in which the substance engaging portion thereof is parallel with the surface of said support and substantially coincidental therewith, and means for guiding said work support while the substance is being sliced, said means for moving said clamp being operable independently of the direction of feed of said work support so that the portion of the substance which is clamped may be varied without changing the direction 55 of feed of said work support, and said clamp cooperating solely with the adjacent surface of the substance to hold the same firmly against the clamp.
- 60 7. In a holder for slicing machines and the like, the combination with a member having an opening therein, surrounded by a substantially flat supporting surface for supporting the substance to be sliced, a clamp arranged within said opening and movable therein to feed a substance along said supporting surface, said clamp 65 having a surface against which the substance to be sliced is clamped, and retractable means movable into and out of a position above said surface on said clamp for holding the substance against said surface of said clamp when desired, said retractable means being movable to an inoperative position so as not to obstruct said surface of said clamp whereby said surface on said clamp and said supporting surface form a combined substance supporting surface on which the substance may be supported independently of the same being clamped and for manual feeding of the substance along said surfaces.
- 70 8. A work holder for slicing machines comprising a substance supporting member, a pivotally mounted substance supporting member having the surface thereof in a plane substantially flush with the supporting surface of said first member and forming a combined surface upon which the substance may be supported and fed manually relatively toward a slicing position, said members being also movable relative to each other during the feeding movement while maintaining said surfaces thereof substantially flush with each other, and retractable substance engaging prongs on the pivotally mounted member for engaging the adjacent portion of the substance and arranged when in operative position to hold the same positively against said last mentioned member and thus maintain a fixed relation between said last mentioned member and the substance while said members are moved relative to each other or when the pivotally mounted member is shifted on its pivot.
- 75 9. A work holder for slicing machines comprising a substance supporting member, a second substance supporting member having the surface thereof in a plane substantially flush with the supporting surface of said first member and forming a combined surface upon which the substance may be supported and fed manually relatively toward a slicing position, said members being also movable relative to each other during the feeding movement while maintaining said surfaces thereof substantially flush with each other, and retractable substance engaging prongs on said second substance supporting member for engaging the adjacent portion of the substance and arranged when in operative position to hold the same positively against said last mentioned member and thus maintain a fixed relation between said last mentioned member and the substance while said members are moved relative to each other, said retractable substance engaging prongs being constructed to engage and hold the substance against lateral shifting movement relative to said member and also prevent movement of the substance away from said member.
- 80 10. A work holder for slicing machines comprising a substance supporting member, a second substance supporting member having the surface thereof in the same plane as the supporting surface of said first member and forming a combined surface upon which the substance may be supported and fed manually relatively toward a slicing position, said members being also movable relative to each other during the feeding movement while maintaining said surfaces thereof in the same plane, and substance engaging prongs on one of said members for engaging the adjacent portion of the substance and arranged when in operative position to hold the same positively against said last

mentioned member and thus maintain a fixed relation between said last mentioned member and the substance while said members are moved relative to each other, said second substance member being pivotally mounted and adapted to swing through various vertical angular positions.

11. In a slicing machine, a work holder for supporting and holding a substance while the same is being sliced, comprising a substance supporting plate having an opening therein with supporting surfaces thereon surrounding said opening on more than one side thereof, a second supporting plate arranged within said opening and having the supporting surface thereof substantially flush with the surface of said first plate, clamping means on said second plate for holding a substance positively against said second plate by engagement with the adjacent portion only of said substance, and means for moving said second plate in said opening in a direction toward the cutting plane of said knife while the surfaces are maintained flush with each other, said second supporting plate being pivoted about axes parallel to the plane of the first plate and being arranged and mounted so that it may be swung from said plane to assume various angles with respect thereto toward the cutting plane of the slicing machine.

12. A work holder for slicing machines comprising a supporting frame slidable in a direction toward a cutting position, a clamp mounted for movement on said frame to various angular positions with respect thereto, means for holding a substance firmly against a surface of said clamp against shifting movement in any direction relative thereto, means for holding said clamp in various angular positions to which the same may be moved comprising an extensible link operable in any desired position of adjustment of said clamp, and means for guiding the substance clamp bodily always in the same direction independently of the angular position to which the clamp is moved.

13. In a work support for slicing machines, the combination with a plate having an opening therein, a supporting member slidably mounted within said opening without changing the angular position thereof with respect to said plate and having the supporting surface thereof in substantially the same plane as said plate, said member being also movably mounted to position the supporting surface thereof at an angle to said plate, and means for clamping a substance against said member while said member is in either of said positions.

14. A substance clamp for slicing machines comprising a trough, having two flat angularly disposed supporting members, one of said members having an opening therein, a plate selectively pivotally or slidably mounted within said opening and movable from a position substantially flush with the supporting surface of said last mentioned member to a position at an angle thereto, and clamping means cooperating with said plate for holding a substance thereon, said plate being slidable toward a slicing position in any of its angular positions of adjustment without changing its angular position of adjustment relative to its supporting surface.

15. A substance clamp for slicing machines comprising a trough having two flat angularly disposed supporting members, one of said members having an opening therein, guides arranged

in said opening substantially parallel to said first mentioned member, a frame slidable on said guides, a plate pivoted to said frame so as to be movable from a position substantially parallel with said last mentioned member and to a position at an angle thereto, and means cooperating with said plate in either of said positions for holding a substance against the same in position to be fed toward the position at which the slices are formed and for preventing relative movement of the substance and plate parallel to the supporting surface of said plate.

16. In a work holder for slicing machines, the combination with a supporting plate, of an auxiliary plate substantially parallel with said first mentioned plate, said first mentioned plate having an opening therein in which said auxiliary plate is movably mounted, a pivot for said auxiliary plate about which said auxiliary plate moves, said auxiliary plate and pivot being bodily movable in unison with each other relative to said first plate, an extensible connection between said pivot and said auxiliary plate to permit said auxiliary plate to be adjusted to various positions relative to said pivot, means for holding said auxiliary plate and pivot in adjusted position with respect to each other, and means for holding said auxiliary plate in any of its adjusted positions about said pivot.

17. In a work holder for slicing machines, the combination with a supporting plate, of an auxiliary plate substantially parallel with said first mentioned plate, said first mentioned plate having an opening therein in which said auxiliary plate is movably mounted, a pivot for said auxiliary plate about which said auxiliary plate moves, said auxiliary plate and pivot being bodily movable in unison with each other relative to said first plate, an extensible connection between said pivot and said auxiliary plate to permit said auxiliary plate to be adjusted to various positions relative to said pivot, means for holding said auxiliary plate and pivot in adjusted position with respect to each other, and means for holding said auxiliary plate in any of its adjusted positions about said pivot, comprising a pair of links pivoted to each other and pivoted respectively to said auxiliary plate and to said first mentioned plate, and means associated with the common pivot for said links for holding said links in adjusted angular position with respect to each other.

18. In a slicing machine, the combination with a slicing knife, of a work support movable relative to said slicing knife having a substance supporting surface with an opening therein, a bearing member slidable beneath the supporting surface and slidably guided by guides on said support for movement in a direction substantially parallel with said supporting surface, a substance clamp pivotally mounted on said bearing member and having a substance engaging surface against which the substance is to be clamped adapted to lie either in a plane substantially coincident with the plane of the supporting surface when said clamp is in one position of adjustment, or in a plane at an angle thereto when the clamp is in another position of adjustment about its pivot, and means for holding a substance to be sliced firmly against said substance engaging surface of said clamp.

19. In a work support for slicing machines, the combination with a plate having an opening therein of a frame slidably mounted in said

opening parallel with said plate, and a supporting member mounted on said frame for sliding movement therewith and adapted to occupy a position in substantially the same plane as said plate, said supporting member being also pivotal-
5 ly mounted on said frame to a position substan-
tially perpendicular thereto, means for holding

a substance on said supporting member against relative movement thereon, and means for feed-
ing said supporting member toward the slicing plane of the machine in all angular positions
of said supporting member.

JOSEPH FOLK.
